CLAIM

The ornamental design for a perfume bottle, as shown and described.

DESCRIPTION

The patent or application file contains at least one drawing executed in color. Copies of this patent or patent application publication with color drawing(s) will be provided by the Office upon request and payment of the necessary fee.

1.1 is a front view;

1.2 is a top view;

1.3 is a bottom view;

1.4 is a side view;

1.5 is a front enlarged view; and

1.6 is a top perspective view.

In the reproductions, the broken lines are for the purpose of illustrating environment only and form no part of the claimed design.
